UNITED STATES PATENT OFFICE.

LEO V. GELDER, OF OAKLAND, CALIFORNIA.

DESIGN FOR A DOMESTIC-BOILER STAND.

57,521.

Specification for Design.

Patented Apr. 12, 1921.

Application filed July 19, 1920. Serial No. 397,513. Term of patent 7 years.

To all whom it may concern:

Be it known that I, LEO V. GELDER, a citizen of the United States, residing at Oakland, in the county of Alameda and State of California, have invented a new, original, and ornamental Design for Domestic-Boiler Stands, of which the following is a specification, reference being had to the accompanying drawing, forming part thereof.

The figure is a perspective view of the stand.

I claim:

The ornamental design for a domestic boiler stand, as shown.

In testimony whereof I affix my signature.

LEO V. GELDER.
